UNITED STATES PATENT OFFICE.

ERNEST H. WEBB, OF NEW BRUNSWICK, NEW JERSEY, ASSIGNOR TO CHASE COMPANIES, OF WATERBURY, CONNECTICUT, A CORPORATION OF CONNECTICUT.

APPARATUS FOR CARDING SAFETY PINS.

Application filed April 12, 1922. Serial No. 551,972.

This invention relates especially to apparatus for carding safety pins and similar articles by forming the cards with transverse or other slots or apertures into which the closed or locked safety pins may be inserted, particularly if the card is transversely arched up when the pins are inserted into the card slots. Then a cardboard or other retainer strip is slipped along the back of the card so as to interlock with the inserted pins and securely and positively retain them in position, the retainer strip being preferably adhesively secured to the card back at a number of places. The card may be conveniently supported and forced into its transversely arched up position in a card holder having inclined card grooves on each side so that when the card is forced longitudinally into the grooves or when the grooved edge portions approach each other the card is arched up transversely along its centre line or where the transverse pin slots are formed therein. A dozen or other desired number of closed safety pins may be placed or fed into a suitable pin transfer block having slots to receive them and thereby be transferred and accurately placed in cooperation with the pin card so that their point portions enter and pass through the card slots sufficiently to allow the retainer strip to be inserted. Then the pins may be ejected from the transfer block by any suitable device and the card released from the holder and discharged therefrom as by the insertion of another unfilled card into the holder.

In the accompanying drawing showing in a somewhat diagrammatic way an illustrative embodiment of this invention:

Fig. 1 is a central longitudinal section through an illustrative carding apparatus.

Fig. 2 is a transverse section thereof taken substantially along the line 2—2 of Fig. 1, and

Fig. 3 is a rear view of the resulting pin card or package.

The pins may be carded or packaged according to this invention while remaining in their closed or locked condition in which they are regularly tumbled and polished and for this purpose the pin card 14 is formed with one or more series of pin slots such as 16 which may be transversely arranged when a single row of pins is to be arranged on the card. The pins preferably have

their point members inserted through these slots which can be readily done by hand or otherwise, especially if the pin card is transversely arched up by any suitable means and when all of these safety pins, rings or other generally similar articles have been inserted into their slots a cardboard or other retainer strip or member 15 is inserted between the card back and the projecting portions of the articles extending through the slots so as to hold them in position during shipment for instance, the retainer strip being preferably adhesively secured to the card back either throughout their cooperating faces or at several points along the same.

An illustrative device for use in forming such a package is shown in Figs. 1 and 2 as comprising a card holder 2 which is preferably formed with a movable side or section 6 mounted to slide laterally on the guide pins 7, 8, each of which may have a threaded end 9 extending into the main card holder 2. A spring such as 29 may be arranged around the reduced end 7 of the pin so as to tend to separate the card holder sections when the bushing 33 is screwed in behind the spring. These sections may, however, be closed by suitable devices such as one or more cams 10 pivoted about the pivots 11 in the ends of the pins 7 so that when the ends 12 of these cams are swung upward into the position indicated in Fig. 2 the card holder sections are closed against the action of these springs 29 and the card 14 is thereby forced up into the transversely arched up position indicated. The card holder is preferably formed with inclined card grooves 5 on either side of the same so that under these conditions the card edges are forced down along these inclined grooves to the curved bottom portions 4 thereof, the arched up lower surface of the card holder recess promoting the desired position of the card adjacent these groove edges.

The safety pins or other generally similar articles may be inserted in any suitable way in these pin slots in the card which are preferably not more than about half as long as the safety pins in order to more definitely hold them in position. For this purpose a pin transfer block such as 18 is desirable in supporting the series of pins and facilitating their insertion in the slots in the card. This transfer block may be formed with a series of pin slots 19 which may extend completely

through the block from top to bottom, if desired, and be spaced apart so as to correspond with the pin slots in the card 14. To retain the pins in position in the transfer block any suitable holding devices such as the pin supporting plates 20 may be employed and mounted, if desired, on the pins 31 projecting from each side of the transfer block 18 and normally forced inward into the position indicated in Fig. 2 by the light springs 21 so that the series of safety pins are thus supported by the inwardly projecting edges of these plates. These plates may, however, be released so as to simultaneously release the series of safety pins from the transfer block and for this purpose the plate releasing cams 22 may be arranged on or adjacent the upper face of the transfer block so as to be engaged by the edges 24 of the pin releasing block 23 during the downward movement toward the transfer block so that it then wedges outward these releasing cams and the connected pin supporting plates 20. If desired also resilient or rigid ejector members may be provided on this releasing block and one or more pin ejector lugs 27 may be formed or yieldably mounted thereon so as to engage the safety pins preferably after the supporting plates have been substantially released and thereupon positively eject the safety pins from the transfer block by passing into the slots 28 in the block. The releasing block may be supported and operated in any desired way as by the tubular carrier members 26 which may extend around the carrier rods 25 secured to the diagonally opposite corners or portions of the transfer block for example, these carrier elements being operated manually or mechanically in any desired way.

In using this apparatus to form the pin package described the pin card 14 may be inserted into the grooved card holder until it engages the card aligner 30 pivoted about the pin 37 to the holder so that it may be swung into this aligning position or swung downward to allow the filled card to be longitudinally discharged from the holder, if desired. When the card is longitudinally positioned in the holder the holder sections may be brought together as by the closing cams 10 so as to transversely arch up the card which may thus be forced up at its central portion somewhat above its transverse guide ribs 3 formed in the upper surface of the card holder and the pin recesses 13 therein as shown in Fig. 1. Then a group of spaced safety pins is brought into registration with the spaced slots in the card by a pin-transfer block 18, so that the point-reaches or the body-reaches, as the case may be, of the respective pins are pushed through the appropriate pin-slots in the card sufficiently to create a passage between such

portions of the pins and the adjacent face of the card into which passage the pin-retainer strip 15 is then inserted by the strip-feeder 1.

Thereupon the pins may be released from the transfer block as by the further descent of the releasing block 23 which releases and ejects the pins from the transfer block and also, if desired, forces portions of the gummed or adhesive surface 32 of the retainer strip into holding engagement with the card back as by the downwardly projecting end portions 34, 35 of the releasing block which may force these card board elements tightly together. The transfer and releasing block may then be withdrawn and the card of pins withdrawn from the card holder preferably after the holder sections have been opened at least to some extent to facilitate this withdrawal.

This invention has been described in connection with a number of embodiments, forms, proportions, parts, arrangements, materials, methods of connection, operation and use, to the details of which disclosure the invention is not of course, to be limited, since what is claimed as new and what is desired to be secured by Letters Patent is set forth in the appended claims.

I do not, in this case, claim any of the specific mechanisms illustrated, described and claimed in the co-pending application of Henry M. Gleason, filed October 8, 1924, Serial No. 742,363.

1. The apparatus for carding safety pins, comprising a multiple section card holder formed with inclined card grooves on either side of its upper surface and formed with an upwardly arching intermediate portion provided with transverse pin recesses, means for closing and opening the sections of said card holder to arch up a transversely slotted pin card having its edges located in said card grooves, a cooperating pin transfer block having a series of transversely spaced pin slots corresponding to the transverse slots in said card, releasable pin supporting plates cooperating with said transfer block to support a series of safety pins in alignment with the slots in said card and a pin releasing block connected to and relatively movable with respect to said transfer block and formed with means to release said pin supporting plates and to positively eject the safety pins from said transfer block when they have been inserted into the slots in said card to be retained therein by a retainer between the back of said card and the projecting pin members in the slots therein.

2. The apparatus for carding safety pins, comprising a multiple section card holder formed with inclined card grooves on either side of its upper surface and formed with an upwardly arching intermediate portion

- provided with transverse pin recesses, means for closing and opening the sections of said card holder to arch up a transversely slotted pin card having its edges located in said 5 card grooves, a cooperating pin transfer block having a series of transversely spaced pin slots corresponding to the transverse slots in said card, releasable pin supports cooperating with said transfer block to support 10 a series of safety pins in alignment with the slots in said card and a pin releasing block connected to and relatively movable with respect to said transfer block and formed with means to release said pin supports. 15
3. The apparatus for carding safety pins or similar articles, comprising a multiple section card holder formed with downwardly inclined card engaging members on either 20 side of its upper surface and formed with an upwardly arching intermediate portion provided with transverse recesses, means for closing the sections of said card holder to arch up a transversely slotted card, a co-operating transfer block having a series of transversely spaced slots corresponding to the transverse slots in said card, means to releasably retain a series of articles in the slots in said transfer block and to disengage them therefrom when they have been inserted in the slots in said card to be retained therein by a retaining member between the card back and the inserted articles. 25
4. The apparatus for carding safety pins or similar articles, comprising a multiple section card holder formed with inclined card engaging members on either side of its upper surface, means for closing the sections of said card holder to arch up a transversely slotted card, a cooperating transfer block having a series of transversely spaced slots corresponding to the transverse slots in said card, means to releasably retain a series of articles in the slots in said transfer block. 35
5. The apparatus for carding safety pins or similar articles, comprising a multiple section card holder formed with inclined card engaging members on either side of its upper surface and formed with an upwardly arching intermediate portion provided with transverse recesses, means for closing and opening the sections of said card holder to arch up a slotted card, and cooperating article holding members. 45
6. The apparatus for carding safety pins or similar articles, comprising a multiple section card holder formed with card engaging members, means for forcing toward each other, the sections of said card holder to arch up a slotted card. 55
7. The apparatus for carding safety pins or similar articles, comprising a card holder formed with cooperating card engaging members adapted to arch up a slotted card, 60 a cooperating transfer block having means to releasably retain a series of articles and to disengage them therefrom when they have been inserted in slots in said card to be retained therein by a retaining member between the card and the inserted articles. 70
8. The apparatus for carding safety pins or similar articles, comprising a card holder formed with means to support and definitely arch up a transversely slotted card, a co-operating movably mounted transfer block 75 having a series of transversely spaced slots corresponding to the transverse slots in said card, releasable supporting plates cooperating with said transfer block to support and transfer a series of articles into alignment with the slots in said card, and a releasing member connected to and relatively movable with respect to said transfer block and formed with means to release said supporting plates and with means to positively eject the articles from said transfer block when they have been inserted into the slots in said card. 80
9. The apparatus for carding safety pins or similar articles, comprising a card holder formed with means to support and arch up a slotted card, a cooperating movably mounted transfer block having a series of spaced slots corresponding to the slots in said card, releasable supporting plates cooperating 85 with said transfer block to support and transfer a series of articles into alignment with the slots in said card, and a releasing member relatively movable with respect to said transfer block and formed with means to release said supporting plates and positively eject the articles from said transfer block when they have been inserted into the slots in said card. 90
10. The apparatus for carding safety pins or similar articles, comprising a card holder to support a slotted card, a cooperating movably mounted transfer block having a series of spaced slots corresponding to the slots in said card, releasable supporting plates 95 cooperating with said transfer block to support and transfer a series of articles into alignment with the slots in said card, and a releasing member connected to and relatively movable with respect to said transfer block and formed with means to release said supporting plates and positively eject the articles from said transfer block when they have been inserted into the slots in said card. 100
11. The apparatus for carding safety pins or similar articles, comprising a movably mounted transfer block having a series of spaced slots, releasable supporting plates 110 cooperating with said transfer block to support and transfer a series of articles, and a releasing member connected to and relatively movable with respect to said transfer block to release the articles from said transfer block. 115
12. The apparatus for carding safety pins or similar articles, comprising a card holder formed with means to support and arch up a slotted card, a cooperating movably mounted transfer block having a series of spaced slots, releasable supporting plates 120 cooperating with said transfer block to support and transfer a series of articles, and a releasing member connected to and relatively movable with respect to said transfer block to release the articles from said transfer block. 125
13. The apparatus for carding safety pins or similar articles, comprising a card holder formed with means to support and arch up a slotted card, a cooperating movably mounted transfer block having a series of spaced slots, releasable supporting plates 130 cooperating with said transfer block to support and transfer a series of articles, and a releasing member connected to and relatively movable with respect to said transfer block to release the articles from said transfer block. 135

12. The apparatus for carding safety pins or similar articles, comprising a movably mounted transfer block having a series of slots, releasable pin supporting elements cooperating with said transfer block to support a series of articles, and a releasing member connected to and relatively movable with respect to said transfer block and formed with means to release said supporting elements and with means to positively eject the articles from said transfer block.

13. The apparatus for carding safety pins or similar articles, comprising a transfer block, releasable pin supporting elements co-operating with said transfer block to support a series of articles, and a releasing member connected to and relatively movable with respect to said transfer block to release and eject the articles from said transfer block.

ERNEST H. WEBB.
